CLAIM

The ornamental design for a vehicle door panel, as shown and described.

DESCRIPTION

FIG. 1 is a front, right side, top perspective view of a vehicle door panel showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a front, right side perspective view thereof.

A mirror image of the vehicle door panel of FIGS. 1-8 is a second embodiment of the vehicle door panel.

1 Claim, 5 Drawing Sheets
